UNITED STATES PATENT OFFICE.

ADOLPH W. GAST, OF CHICAGO, ILLINOIS, ASSIGNOR TO CHICAGO MINIATURE LAMP WORKS, OF CHICAGO, ILLINOIS, A CORPORATION OF ILLINOIS.

SIGN LETTER.

Application filed December 26, 1924. Serial No. 757,980.

This invention relates to a novel and improved sign letter or character and consists of the matters hereinafter described and more particularly pointed out in the appended 5 claim.

The invention relates to an illuminated sign letter of the kind in which the letter or character is illuminated from within, as distinguished from sign letters or characters outlined by exposed lamps, and includes a translucent letter plate, either flat or raised to outline the character or letter, with a stencil plate or equivalent means for blocking out and defining the letter or character on the plate. The letter plate is generally and preferably made of what is commonly known as opal glass, which is a translucent, milk-white glass of such density as to transmit light rays and brilliantly illuminate the glass plate in 10 the part where the rays are transmitted, while preventing the bright glow of the illuminating means from being visible through the glass. The plate is sometimes colored, but for the purpose of brilliancy in a day sign, 15 as well as for a night sign, white is preferable.

Signs of the kind as now generally constructed consist of an elongated box with one or both of its long sides containing the stencil 20 plate which outlines the letters or characters, with the glass letter plates secured thereto in such manner that where raised letters are used, the letter strokes project through the stencil plate; and with electric light bulbs in 25 sufficient number contained within the box to properly illuminate the sign.

Signs of the kind, while effective when first put out, soon lose their brilliancy. Being exposed to the weather, the letter plates become soiled, both on the inner faces and on the 30 outer faces of the character strokes, so that the letters soon become dull and dark on account of the obstruction to the transmission 35 of light due to the accumulation of dust and soot on the inner and outer faces of the plate, and on account of the reduction of reflecting capacity of the inner face of the letter plate. The letter plates may be washed, but a thorough 40 cleaning of the inner faces of the plates is almost impossible and it is very difficult, if not impossible, to restore the original brilliancy of such a sign by mere washing. In 45 any case, the necessity for frequent washing

and cleansing of the sign plates adds greatly to the expense of the upkeep of the sign. 55

Again, the brilliancy of the sign is affected by the number of lamps used, and as a large amount of current is required to maintain the usual electric globes employed at proper incandescence, there is not only a considerable expense involved for use of current, but in addition, the lamps frequently burn out, requiring replacement, which likewise adds to the expense of the upkeep. 60

The object of my invention is to produce 65 a novel sign letter or character unit of simple and economical construction, including a letter plate of the kind above described, which unit is individually illuminated and which may be used in any assembly or arrangement 70 of units of similar kind to provide a sign upon an ordinary board or other support. The novel unit is entirely enclosed and sealed so that it is impervious to dust, soot and moisture and is not subject to changes or deterioration by reason of weather conditions. 75

The novel letter or character unit includes 80 an illuminating device, an electric lamp or globe which will produce a maximum of light diffusion with a minimum of light concentration, so that the said lamps may be brought comparatively close to the letter plates with a resulting reduction in the wattage consumed by the lamps and a substantial reduction in the depth of the letter unit 85 casing or enclosure so that the units may be used to make either double or single face signs without presenting excessive depth or width between the faces of the sign.

These and other advantages of my invention 90 will appear more fully as I proceed with my specification.

In the drawings:—

Figure 1 is a view representing a front elevation of the improved letter or character 95 unit.

Figure 2 is a side elevation of the same.

Figure 3 is a view representing on an enlarged scale, a fragmentary part of the unit in front elevation, with parts broken away. 100

Figure 4 is a view representing on an enlarged scale a partial vertical section through the unit in a plane indicated by the line 4—4 of Figure 1.

Figure 5 is a view on the same scale as 105 Figures 3 and 4, representing a partial sec-

tion through the unit in a plane indicated by the line 5—5 of Figure 2.

Figures 6 and 7 are sectional views similar to Figure 3 showing the illuminating lamps arranged in different ways.

Figure 8 is a view representing in front elevation a slightly modified form of the improved letter or character unit.

Figure 9 is a view representing a side elevation of the same.

Figure 10 is a perspective view on a somewhat smaller scale of the shell or casing of the unit shown in Figures 8 and 9.

Figure 11 is a perspective view of a letter plate with a raised letter therein.

Figure 12 is a perspective view of a letter plate which is flat.

Figure 13 is a view representing a transverse section through another modified form of the invention.

Referring now to that embodiment of the invention illustrated in the drawings: 20 indicates a shallow box or casing having a top wall 21, a bottom wall 22 and a back wall 23.

25 Said casing is open on its front side, which is closed as will presently appear, by the letter plate. This casing forms the body of the unit, and is of such lateral and vertical dimensions as may be required by the size of the letter plate.

The unit is generally intended to contain but a single letter or character; but this will depend upon the size of the letter or character and also upon the manner in which the unit is 35 to be used. As shown in the drawings, I have presented the unit as containing but a single letter or character, as will be the case where the letters or characters are of large dimensions.

40 24 indicates the letter plate. As illustrated, this is the familiar white, translucent glass plate, preferably opal glass, and as shown bears a raised letter or character 25 which presents a convex outline toward the front or face of the unit, and a concave outline toward the interior of the unit. The letter plate is supported in any convenient manner at the open side of the casing 20,—in this case, being supported against an open frame

45 26, the members of which are made in the form of an angle bar with a flange 27 in a vertical plane, against which the marginal part of the letter plate is secured, and a flange 28 at right angles to the vertical flange, which is secured by rivets or otherwise to the bottom, side and top walls of the box or shell 20 in a position adjacent the open front thereof.

50 The edges 29 of the letter plate fit loosely within the marginal parts 30 of the walls of the casing and are held and sealed therein against the entrance of dust, soot and moisture in any suitable manner as for example by a hard, quick drying wax or gum 29^a (see Figure 4), together with packing or not as 55 may be required to seal the joint and to re-

tain it in sealed relation under the weather conditions to which it is apt to be exposed. The sealing wax or gum should be of such character that it has, when set, the required elasticity to take up any expansion of the letter plate or other parts. Preferably a gum which will soften when heat is used, since manifestly such gum will yield when the letter plate expands upon a rise of temperature.

75 The front face of the letter plate as shown in Figures 1 to 7 inclusive are without covering or coating. But when assembled in a sign, the character strokes 25 of the letter may be outlined or defined in any suitable or well-known manner, either by opaque paint, or by a thin sheet metal stencil plate which will be placed in the position indicated by dotted lines at 31. Thus, the outer face of the letter plate will then be entirely coated or covered so that it is impervious to the transmission of light rays, except the part or parts which constitute the stroke or strokes of the letter. The outer face of the letter plate may be otherwise treated to present the letter strokes on 90 a distinctly contrasting background.

95 The walls of the casing 20, and the inside face of the letter plate are coated with white or other reflecting paint which will substantially obstruct the transmission of the light and reflect substantially all light rays directed against it. This is important as every part of the inside surface of the unit should constitute an efficient reflecting surface. This greatly adds to the brilliant effect of the letter or character. The only exception to this, is that part of the letter plate which constitutes the stroke or strokes of the letter or character, namely, the part 32. This part is not only not painted, but the glossy surface of the glass plate, as when opal glass is used, is sand blasted or otherwise treated so as to prevent any possibility of a reflection of the light within the unit from the back or inner surface of the parts constituting the strokes of the letter or character. In this way every bit of light which reaches the strokes is transmitted and little or none of it is lost by reflection. On the other hand, by painting the inner face of the glass plate on the parts not covered by the strokes of the letter or character, as above set forth, no light rays are lost by absorption in the glass plate. Thus, the full efficiency, both by direct transmission and by reflection of the light within the unit is concentrated upon and transmitted through the letter strokes.

110 115 120 125 130 The tone or color of the reflecting paint affects the color of the letter. Thus when a white letter is desired a perfectly white reflecting surface, whether painted or otherwise, is essential for the most brilliant effect. A paint which will not oxidize and turn yellow is desirable. Thus suitable coloring of the inner reflecting surfaces of the sign acts

in aid of the coloring effect in the letter stroke when color is used.

The preferred lamp used in the unit is one of low wattage consumption adapted to produce a maximum of light diffusion with a minimum of light concentration. A lamp of the kind also distributes the heat instead of concentrating it, which is important since the unit, being enclosed and sealed, there is no escape for the heat of the lamps by ventilation as in other signs, but only by conduction from the walls of the unit to the atmosphere. Such a lamp is indicated at 33. Said lamp consists in its preferred form of an elongated tube or bulb 34 of comparatively small diameter and of substantially the length of the distance between the top and bottom walls 21, 22 of the unit casing, with a plurality of longitudinally spaced small filaments 35 located therein. The tube is mounted on an elongated insulation back 36 which contains the conductor wires (not shown). Said wires are led forth from one end of the base, the top as shown, to a lamp cord 37. An opening 38 is made in the top or bottom wall of the casing, (in this case the top wall 21), for the introduction of the lamp, which is supported in position by a plate or base 39 which projects as a flange on all sides beyond the limits of the opening 38 so as to rest upon said top wall and support the depending lamp within the casing. The base plate 39 is removably secured to the top wall 21 in any convenient manner as by butterfly nuts and screws 40, with a washer 41 interposed between the plate 39 and the said top wall to seal the lamp within the casing.

A lamp of the kind best adapted for use in the improved unit is shown and described in Letters-Patent Number 1,043,821, granted to me on the 12th day of November, 1912.

Depending upon the character or letter embodied in the unit, one or more of such lamps are used. As shown, in the drawings, two lamps are provided and are generally required in the unit for proper diffusion. These lamps may be placed comparatively close to the letter plate without any danger of the reddish glow of the filaments being observable through the strokes of the letter or character. Since they may be placed thus close, the current required to supply the lamps is of greatly reduced wattage as compared to that required in the ordinary incandescent lamps now used in illuminated signs where the lamps are necessarily placed a further distance away in order to get proper distribution. Lamps of the kind have a much longer life owing to the fact that it is not necessary to heat the filaments to such high incandescence as in the case of other lamps. As the lamp globe itself may be placed so near to the letter plate, the depth of the sign unit from the glass plate to the back wall is made comparatively small.

The lamps may be placed, as shown in Figure 6, so as to cast the light directly through the letter strokes, as indicated by the broken lines in said figure, or the lamps may be reversed with their backs toward the letter plate, as indicated at 33^x in Figure 7, so that the illumination of the strokes is entirely by reflection or indirect lighting, as indicated by the broken lines. In this case, but a single lamp is required for proper diffusion. In such case also there is no possibility whatever of the glow of the lamps being observable through the letter strokes, even when glass of lesser density than the opal glass is used for the letter plate. The arrangement of the lamps in this way makes it possible to use standard lamp globes of some types, provided with a suitable back or backing, in a comparatively shallow unit casing, without danger of the glow of the filament being observable through the strokes of the letter.

As hereinbefore mentioned, the letter plate may be either one which bears raised letters or it may be flat, in either case, however, being made of the required density. The raised letter plate 24^a of familiar construction is shown in perspective in Figure 11, wherein the treatment of the inner face of the letter plate throughout the strokes of the letter or character is indicated by the dots 42, which show where the plate has been sand blasted or otherwise treated to remove the gloss and destroy its reflecting character. A flat letter plate 24^b, that is one without a raised letter, is shown in perspective in Figure 12. Here again the plate is treated on its inside face throughout the stroke of the letter or character as indicated by the dots 43 to remove the gloss by sand blasting or otherwise. The rear surface of the letter stroke treated in this manner also acts to finally break up and distribute the light rays, thereby removing the last possibility of concentration.

The letter unit may be provided with any desirable flanges or base suitable for assembling it with like units and mounting it upon a proper support as a signboard or the like. In Figures 1 and 2, angular brackets 44, 44 are attached to the top and bottom walls of the unit casing at the front thereof by means of which the unit may be conveniently secured at top and bottom to an open frame (not shown) which is designed to provide a support for the units, and which includes the familiar stencil plate indicated by the dotted lines 31 in Figure 4.

In Figures 8 to 10 inclusive, I have shown a somewhat modified form of the unit. In this case 20^x indicates the unit and 25^x the letter plate, other corresponding parts being indicated by numerals like those used in first describing the unit but with the superfix "x". The unit shell is provided at its front open side with a recessed, marginal open frame 45 to receive the letter plate. 46 indicates the

recess (see Figure 10), in which the said plate is placed, with its back against the shoulders 47 and its edges loosely engaged within the shoulders 48, and being sealed as before. The shoulder 48 is somewhat greater in depth than the thickness of the letter plate, so that said plate is set back from the face 49 of the frame 45.

The letter plate is painted on its outer face 10 except at the letter strokes in order to block out the letters, so that the unit in this instance is ready for assembly with others on a suitable support by means of horizontal flanges 50, 50 at the top and bottom of the frame 45, 15 without the use of a stencil plate. This construction is sometimes preferred, since the absence of the stencil plate eliminates the possibility of water or moisture, whether from the weather or from washing, getting between the letter plate and the stencil plate, when it is likely to cause rust and in time produce rust streaks to mar the face of the letter plate.

In the units hereinbefore described, a letter plate is used upon but the one side of the 25 unit, and this is the manner in which the unit will generally be made in order to meet all conditions in both single and double face signs. In some cases, however, the back closure of the unit casing as well as the front 30 closure, may be provided by a letter plate in which case the unit itself will be double face, with a letter plate presented on both faces.

Such a modification of the letter unit is shown in Figure 13 wherein like parts are all 35 indicated by like numerals with the superfix "y". 51 indicates the additional letter plate which forms the back closure of the casing

20^y. Said letter plate is mounted and sealed within the margins of the top, bottom and side walls of the casing at the back in the 40 same way as the letter plate 25^y is mounted and sealed therein at the front, as heretofore described. In this case the lamps 33^y have their insulation backs 33^y, if such backs be used, turned towards the side walls of the casing. 45

While in describing my invention, I have referred to many details of form and of mechanical construction and arrangement of parts, it is to be understood that the invention is in no way limited thereto, except as 50 may be pointed out in the appended claim.

I claim as my invention:

An illuminated sign letter unit comprising a shallow casing closed on all sides but open in front, a translucent glass letter plate closing the open front of said casing, means for sealing the edges of said letter plate in said casing, said means being adapted to take up the expansion of said plate under changes of temperature, and a removable lamp of low 60 candle power but of wide diffusion sealed in said casing but removable therefrom, the candle power of said lamp and the density of said letter plate being so correlated to the depth of said casing and to each other that 65 said letter plate will be brilliantly and evenly illuminated without concentration of direct light at any point or points of said letter strokes, and means for removably supporting and sealing said lamp in said casing. 70

In testimony that I claim the foregoing as my invention, I affix my signature this 22d day of December, A. D. 1924.

ADOLPH W. GAST.
